UNITED STATES PATENT OFFICE.

ANDREW J. ENGLISH, OF CINCINNATI, OHIO, ASSIGNOR TO THE WALTER ELEVATOR COMPANY, OF SAME PLACE.

APPARATUS FOR CARBURETING AIR OR GASES.

SPECIFICATION forming part of Letters Patent No. 308,886, dated December 9, 1884.

Application filed July 10, 1884. (No model.)

To all whom it may concern:

Be it known that I, ANDREW J. ENGLISH, a citizen of the United States, residing at Cincinnati, Ohio, have invented new and useful

5 Improvements in Apparatus for Carbureting Air or Gases for Illuminating Purposes, of which the following is a specification.

My invention relates to that class of gas-machines in which atmospheric air or gas is forced through suitably-arranged carbureting-chambers in contact with a volatile hydrocarbon liquid, with a view to the saturation of the gas with the hydrocarbon vapors, to be used for domestic, industrial, or illuminating 15 purposes; and it consists, first, in the construction and arrangement of means for the automatic supply of liquid to the carbureting-chambers as needed, and, second, in the provision and arrangement of means for indicating the exhaustion of liquid from the supply chamber or reservoir.

In the accompanying drawing is shown a vertical section of a carbureting-chamber embodying my improvements, in which A designates the main carbureting-chamber, and $a' a^2 a^3$ the internal carbureting-chambers; b b, the partitions dividing the same from each other; $p' p^2$, the inflow and outflow air pipes; R, the reservoir; p^3 , the overflow-pipes between the 20 carbureting-chambers, these parts being constructed and arranged in the usual manner, and the chambers being channeled and provided with absorbent material (not shown in the drawing) to assist evaporation.

35 To secure the automatic feeding of the chambers $a' a^2 a^3$, I place in the bottom B of the reservoir R a valve-seat and opening, o, controlled by a lift-valve, v, the latter connected by rods $r' r^2$ and a pivoted connecting-lever, l, 40 with a float, f, arranged in the lower carbureting-chamber, a' . The lever l is mounted upon a suitable supporting-frame, c, or it may be hung from top of the reservoir R, and the rod r^2 is carried down through an open tube, t, 45 passing from a point above the highest level of the liquid in the reservoir R into the lower chamber, a' , through the separating-partitions. The construction is clearly shown in the drawing, and the float f should be of sufficient 50 weight to elevate the valve with certainty.

against any tendency of the latter to "stick" from any cause, yet to rise with the liquid and close the valve when the proper level is attained.

It will be apparent that as the greatest consumption of liquid takes place in the lower chamber, where the air or gas is first admitted, and as the chambers are furnished with overflow-pipes, the feeding will take place continuously as long as any liquid remains in the upper chamber, R—that is, a very slight diminution of liquid in the lower chamber, a' , will allow the float f to fall, which, acting by its weight on the rod r^2 and lever l, will lift the valve v from its seat, allowing the liquid to 55 flow into chamber a^3 , thence, when the top of the overflow-pipe p^3 is reached, into the chamber a^2 , and similarly, by pipe p^2 therein, into the chamber a' , where equilibrium will be established by the raising of the float f and consequent closing of valve v. It will thus be 60 seen that as a slight lowering of liquid in chamber a' is accompanied by a lesser lowering in chamber a^2 , and one still less in chamber a^3 , the quantities of liquid contained in 65 the several chambers will bear a constant relation to each other—such that as long as any liquid remains in the upper chamber the valve v will deliver it continuously and in just the 70 quantity required for consumption.

To determine when the chamber R becomes nearly empty, I provide a tube, t, (through which rod r^2 , carrying the float f, passes,) and which also passes through the horizontal partitions b of the carbureting-chambers $a' a^2 a^3$, 75 and, furnishing communication between the top of the upper reservoir, R, and the top of the lower chamber, a' , acting also as a vent and allowing ready escape of liquid through valve v by equalizing pressure. Two test-pipes, $w' w^2$, are also provided, issuing from the side of reservoir R, near the bottom, but at different heights, and provided with whistles or similar devices, g, at their upper ends, and closed by cap-screws. Upon unscrewing 80 the cap u from tube w' , should the level of liquid in reservoir R have fallen below the opening s, the air or gas entering at p' in lower chamber, a' , will pass by means of pipe t to the reservoir R, and thence out through pipe 85 90 95 100

5 w' , giving warning by blowing the whistle g . A similar test may be made with the pipe w^2 , which will in turn indicate the fact, should the level of liquid in R be below the orifice s' , when the reservoir R will be empty.

10 A supply-pipe, S , furnishes the means of filling the empty reservoir, and may also serve as a test-pipe, when provided at the top with lateral branch pipe and whistle g , closed ordinarily by a cap. If the reservoir be empty, on unscrewing the cap the whistle sounds. The vent-pipe y allows air to escape while filling the reservoir.

15 To provide for the escape of water condensing in the gas or air supply pipe p' , I provide in the latter an outlet-pipe, p^4 , with a cock, K , and a small collecting-chamber, C , at or near the entrance to the chamber a' , communicating with the open air. On opening the 20 cock at intervals any moisture will be expelled.

I claim as my invention and desire to secure by Letters Patent of the United States—

25 1. In a gas-carbureting machine embodying a reservoir arranged above a series of carbureting-chambers, the latter provided with short overflow-pipes connecting the chambers, the lower chamber being the air or gas entry, the float f in the lower chamber, the rod r^2 , 30 connecting the float and a lever, l , through the open tube t , (said lever being pivoted to said rod,) the lever l carrying pivoted at one end the float-rod r^2 , and at the other end the valve-actuating rod r' , and being pivotally supported at an intermediate point in the oil-supply reservoir R , (said point being so placed 35 that a slight movement of the float causes greater movement of the valve,) the rod r' ,

fixed to the conical valve v , seated in the bottom of the reservoir, and surrounded by suitable protecting netting, the open tube t , furnishing free air or gas communication between the lower chamber, a' , and the oil-supply chamber R , and surrounding the float-rod r^2 , the whole combined, arranged, and operating as and for the purpose specified.

2. In a carburetor having an oil-reservoir above a series of carbureting-chambers connected in series, a pipe, t , surrounding the float-rod r^2 , and providing air communication between the oil-reservoir and lower air-entry chamber, in combination with the air-entry chamber a' , oil-supply reservoir R ; and test-tubes w' w^2 , (one or more,) having attached above whistles or call-indicators g , actuated by the passage of gas outward therein, said tubes entering the lower chamber at different heights, substantially as described.

3. In a carburetor having an oil-reservoir above a series of carbureting-chambers connected in series, and with tube t , connecting the top of oil-reservoir and lower air-entry chamber, the combination of oil-reservoir R , tube t , air-entry chamber a' , air-pipe p' , and the enlarged chamber at or near the air-entry point on the air supply-pipe provided with outlet-pipe p^4 , stop-cock K , and a manipulating-handle extending upward, arranged and operating substantially as set forth.

In testimony whereof I have hereunto set my hand in the presence of two subscribing witnesses.

ANDREW J. ENGLISH.

L. M. HOSEA,
C. F. SHAPPEL.

Correction in Letters Patent No. 308,886.

It is hereby certified that in Letters Patent No. 308,886, granted December 9, 1884, upon the application of Andrew J. English, of Cincinnati, Ohio, for an improvement in "Apparatus for Carbureting Air or Gases," the name of the assignee of said invention was erroneously written and printed "The Walter Elevator Company," instead of *The Water Elevator Company*; and that the proper correction has been made in the files and records pertaining to the case in the Patent Office, and should be read in the Letters Patent to make it conform thereto.

Signed, countersigned, and sealed this 23d day of December, A. D. 1884.

[SEAL.]

M. L. JOSLYN,
Acting Secretary of the Interior.
